UNITED STATES PATENT OFFICE.

VETA L. MILLER, OF CHEYENNE, WYOMING.

ARTIFICIAL LEG.

1,113,366.

Specification of Letters Patent. Patented Oct. 13 1014.

Application filed April 29, 1914. Serial No. 835,224.

To all whom it may concern:

Be it known that I, VETA L. MILLER, a citizen of the United States, residing at Cheyenne, in the county of Laramie and State of Wyoming, have invented certain new and useful Improvements in Artificial Legs, of which the following is a specification, reference being had to the accompanying drawings.

10 This invention relates to artificial legs.

All wearers of artificial legs are familiar with the difficulty encountered in attempting to remove the trousers leg over the foot, or to change the shoe, this being due to the fact 15 that the foot will not yield so as to permit the trousers readily to be slipped over it, and for the same reason it is exceedingly difficult to position a shoe on the foot.

The object of the present invention, is in 20 a ready and practical manner so to construct an artificial leg as to enable the wearer thereof to remove the foot without detaching the socket from the limb, so that should he desire to change his trousers or shoes no 25 more trouble would be encountered than would be by a person whose limbs are intact.

With the above and other objects in view, as will appear as the nature of the invention is better understood, the same consists, generally stated, in an artificial leg embodying a two-part socket, the members of which are arranged for telescopic connection, and one of which carries the foot, means being provided whereby the foot carrying section of 30 the socket may readily be detached from the leg engaging section, thus to permit removal of the trousers, or to combine a dress shoe with the leg. With the arrangement employed, any form of artificial leg may be 35 used, it only being necessary to divide the socket at any point above the line of the shoe top and connect the two sections by a telescopic joint, combined with which are spring catches or latches which will operate 40 to hold the leg sections assembled and permit of their ready disconnection when desired.

Further and more specific details of construction will be hereinafter fully described 45 and claimed.

In the accompanying drawing, forming a part of this specification, and in which like characters of reference designate corresponding parts; the figure is a view in side 50 elevation, partly in section, of an artificial

leg equipped with the improvements of the present invention.

In describing the invention, the construction of the leg will be given only general terms, as the invention will be applicable to any style of leg, whether it be for one used in amputations above or below the knee. In the present instance the latter form of leg is shown, and the socket is exhibited as constructed of two sections 1 and 2, the meeting point of the two sections being at or slightly above the line of the top of the shoe. The upper or leg engaging section has secured around its lower end, as by rivets or the like, a metallic collar 3 which is designed to telescope snugly within a sleeve 4 carried by the foot carrying section 2, the sleeve being constructed of metal, and secured to the leg section by rivets or the like. The section 2 is provided with the usual bridge piece 5 with which connects the upper ends of tendons 6 and 7, the lower ends of the tendons being, as usual, secured in the foot 8, and the tendon 7 having combined with it an ordinary extensor spring 9. The foot is provided with the usual socket 10 to which is hinged the lower end of a frame member 11, the upper end of which is rigidly secured to the inner wall of the section 2 below the bridge piece. As will be seen, by this arrangement all of the working parts of the foot are below the point of juncture between the two socket sections, so that it will not require any disconnection of any of the working parts to remove the foot and socket member 2 from the socket member 1.

Any suitable means may be employed for holding the two leg sections firmly assembled when the collar and sleeve are telescoped, that in the present instance consisting of the provision of two spring catches 12, which may be arranged at the front and back of the leg section 1, or at the sides thereof, and are firmly secured thereto, the lower ends of the catches being provided with orifices 13 to receive pins 14 carried by the sleeve 4. It is designed that the contact between the sleeve and collar shall be a snug one, so that the two parts of the socket will be prevented from having any wobbling motion, so that undue wear between the parts will be eliminated, and unpleasant noises avoided.

It is to be understood, of course, that the

- invention will not be limited to the precise arrangement shown, as it will be obvious that the disposition of the parts could be reversed, that is to say, the collar could be placed upon the section 2 and the sleeve upon the section 1, and the latches secured to the former section, and still secure the object sought, and as this will be evident, detailed illustration thereof is omitted.
- 10 Having thus described my invention, what I claim is:
1. An artificial leg comprising a two-part socket one of which carries a foot, and means for detachably connecting the parts where-
  - 15 by to remove the foot from the socket proper when the latter is in place.
  2. An artificial leg comprising a two-part socket one of which carries a foot, a sleeve secured around one of the sections, a collar secured around the other section and ar-
- ranged to receive the sleeve, and locking means carried by one of the sections and co-acting with the sleeve to prevent accidental disconnection of the parts.
3. In an artificial leg, a leg socket composed of two sections, one of which carries a foot, a sleeve secured exteriorly of the upper end of the foot section, a collar surrounding the lower end of the leg section and arranged to be received in the sleeve, 25 spring catches carried by the leg section, and pins or studs carried by the sleeve to engage with the spring catches.
- In testimony whereof I hereunto affix my signature in the presence of two witnesses. 30

VETA L. MILLER
